(57) **CLAIM**

The ornamental design for a air purifier mask body, as shown and described.

DESCRIPTION

FIG. 1 is a front, right side, perspective view of a air purifier mask body showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view showing an exploded perspective view in which filters and sealer parts are combined in the body.

The broken lines indicate portions of the article that form no part of the claimed design.

The broken lines showing of the portion of filters and sealer parts in FIG. 8 are for the purpose of illustrating environmental structure and form no part of the claimed design.

1 Claim, 8 Drawing Sheets
